CLAIM

I claim the ornamental design for a surface mountable gutter, as shown and described.

DESCRIPTION

FIG. 1 is a top perspective view of a first embodiment of a surface mountable gutter, showing my new design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof.

FIG. 7 is a bottom plan view thereof.

FIG. 8 is a top perspective view of a second embodiment of the surface mountable gutter, showing my new design.

FIG. 9 is a front elevational view thereof.

FIG. 10 is a rear elevational view thereof.

FIG. 11 is a left side elevational view thereof.

FIG. 12 is a right side elevational view thereof.

FIG. 13 is a top plan view thereof; and,

FIG. 14 is a bottom plan view thereof.

The surface mountable gutter is shown with symbolic breaks in its length. The appearance of the surface mountable gutter between the break lines forms no part of the claimed design. The broken lines in the drawings illustrate portions of the surface mountable gutter that form no part of the claimed design.
